UNITED STATES PATENT OFFICE.

ROBERT W. TAYLOR, SR., OF KALAMAZOO, MICHIGAN, ASSIGNOR TO EVANSVILLE ARBOR PRESS COMPANY, OF EVANSVILLE, INDIANA.

MANDREL-PRESS.

1,397,910.

Specification of Letters Patent.

Patented Nov. 22, 1921.

Application filed June 19, 1920. Serial No. 390,276.

To all whom it may concern:

Be it known that I, ROBERT W. TAYLOR, Sr., a citizen of the United States, residing in the city and county of Kalamazoo and State 5 of Michigan, have invented certain new and useful Improvements in Mandrel-Presses, of which the following is a specification.

This invention relates to improvements in mandrel presses.

10 The main objects to this invention are to provide in a mandrel press an improved work table which may be quickly and easily adjusted to work of different kinds and sizes and at the same time one which is very 15 strong and rigid.

Further objects, and objects relating to structural details, will definitely appear from the detailed description to follow.

10 The invention is clearly defined and pointed out in the claims.

A structure which is a preferred embodiment of my invention is clearly illustrated 25 in the accompanying drawing, forming a part of this specification, in which:

Figure I is a rear perspective view of a mandrel press embodying the features of 30 my invention.

Fig. II is a horizontal section on a line corresponding to line 2—2 of Fig. I but with the main table members shown in full lines in operative position and by dotted lines in 35 inoperative position.

Fig. III is a similar horizontal section showing the table members in another adjustment by full lines and still another adjustment by dotted lines.

40 Fig. IV is a similar horizontal section with the auxiliary table member shown in operative position by full lines and in inoperative position by dotted lines.

In the drawing similar reference characters refer to similar parts throughout the several views.

Referring to the drawing, the frame comprises the base 1, uprights 2, 2 and 3 supporting the top plate 4. The uprights are 50 supported in triangular position upon the base with the upright 3 at the rear. The top plate constitutes a support for the ram 5 and its driving mechanism which is provided with a gear housing 6. The driving 55 means for the ram are not illustrated or de-

scribed in detail as they form no part of this invention. The mechanism is preferably that, however, shown and described in detail in the U. S. Letters Patent to Frank Burtt, Patent No. 1,356,905, dated October 26, 1920, 60 my improvements being commercially embodied in machines having the features there shown.

I provide a pair of work tables members 7 pivoted on the uprights 2 and provided 65 with foot portions 8 resting on the flat ways 9 when the table members are adjusted to operative position. The table members have coacting top portions 10 eccentric relative to their axis and spaced from the base so 70 that the spaces may be varied by swinging the members thus adapting them to receive arbors of different diameters.

The table members 7 may be swung to inoperative position and entirely out of the 75 way as shown in dotted lines in Fig. II.

I also preferably provide an auxiliary table member 11 pivoted upon one of the uprights 2 and adapted to swing over and rest upon the top portions 10 of the main table 80 members 7. The table member 11 has a vertical channel 12 which is aligned with the spaces between the top portions of the table members 10. A work holder 13 having openings 14 of different sizes adapted to be 85 brought over the channel 12 is rotatably mounted on the table member 11.

With this arrangement of parts the table member may be quickly adjusted to adapt them to the particular work and they are 90 very strong and rigid.

I have not attempted to illustrate certain adaptations and modifications which I contemplate as I believe the disclosure made will enable those skilled in the art to which 95 my invention relates to embody or adapt the same as may be desired.

Having thus described my invention, what I claim as new and desire to secure by Letters Patent, is:

1. In a mandrel press, the combination of 100 a frame comprising a base and a pair of uprights, a pair of main table members journaled on said uprights to be swung to operative position over said base and provided 105 with foot portions resting on the base when in operative position and with coacting top portions eccentric relative to their axes and spaced from said base so that the spaces between them may be varied by 110

swinging the members, an auxiliary table member pivotally mounted on one of said uprights to be swung over and rest upon the top portions of said main table members, 5 said auxiliary table member being provided with a vertical work channel adapted to be alined with the space between the top portions of said main table members, and a work holder rotatably mounted on said auxiliary table member.

2. In a mandrel press, the combination of a frame comprising a base and a pair of uprights, a pair of main table members journaled on said uprights to be swung to 15 operative position over said base and provided with coacting top portions eccentric relative to their axes and spaced from said base so that the spaces between them may be varied by swinging the members, an auxiliary table member pivotally mounted on 20 one of said uprights to be swung over and rest upon the top of portions of said main table members, said auxiliary table member being provided with a vertical work channel 25 adapted to be alined with the space between the top portions of said main table members.

3. In a mandrel press, the combination of a frame comprising a base and a pair of uprights, a pair of table members journaled on 30 said uprights to be swung to operative position over said base and provided with foot portions resting on the base when in operative position and with coacting top portions eccentric relative to their axes and 35 spaced from said base, so that the space between them may be varied by swinging the members.

4. In a mandrel press, the combination of a frame comprising a base and a pair of uprights, a pair of table members journaled on 40 said uprights to be swung to operative position over said base and provided with coacting top portions eccentric relative to their axes and spaced from said base, so 45 that the space between them may be varied by swinging the members.

In witness whereof, I have hereunto set my hand and seal in the presence of two witnesses.

ROBERT W. TAYLOR, Sr. [L.S.]
